UNITED STATES PATENT OFFICE.

JOHN THOS. FAIRHURST, OF BROOKLYN, NEW YORK.

CABINET.

1,273,838.

Specification of Letters Patent. Patented July 30, 1918.

Application filed September 28, 1916. Serial No. 122,761.

To all whom it may concern:

Be it known that I, JOHN THOS. FAIRHURST, a subject of the King of England, residing at the borough of Brooklyn, in the county of Kings and State of New York, have invented certain new and useful Improvements in Cabinets, of which the following is a specification, reference being had therein to the accompanying drawing.

10 My invention relates to improvements in folding or collapsible doors, windows, or partitions more particularly adapted for use in combination with cabinets, closets, or other suitable chambers, such as bookcases.

15 Referring to the accompanying drawings Figure 1 is a view in front elevation partly broken away showing a suitable form of closet with one set of folding doors folded out on one side and opened in on the other,

20 and Fig. 2 is a horizontal section of the same. Fig. 3 is an enlarged horizontal section of one set showing the folding door or partition on one side in a position to enter or leave the recess within which it is stored

25 when not in use.

1 indicates the frame of a suitable closet or case opened in the front at one side as indicated at 2. 3—4 indicate a pair of doors or sections suitably hinged together as indicated at 5, and 6—7 indicate another pair of such doors folded into the closet or case at the left side looking at Figs. 1 and 2. 8—9 are suitable handles for operating the doors or sections.

35 Each pair of doors is pivotally secured at the top by a suitable bar or rod such as 10, and the same may be provided at the bottom if desirable, the pivot engaging the groove 16 as shown. The bar or rod 10 is also tele-

40 scopically, or slidably connected with the bar 11 allowing for movement equal to the length of the slot 12 in the rod 11 which is preferably hollow; the pin 13 upon the rod 10 serving as a guide or stop. The other 45 end of the rod 11 is also pivotally secured at 14 which may be a shaft extending entirely down the back of the closet, if necessary, to provide similar pivotal support for a similar set of rods at the bottom of the

closet. This arrangement insures the same movement at the top and bottom and prevents jamming or wedging of the doors therebetween. 15—16 are suitable guides for the doors 3—4 respectively, and the guide 15 is also preferably extended across the front 55 of the closet as indicated at 17 to guide the inner side of the door 3, as shown.

From the foregoing it will be seen that the outer end of the door 4 looking at Fig. 1 will always be maintained in vertical alignment or perpendicular, and that the doors may run across the front of the closet as illustrated in Fig. 1, or may be collapsed and pushed into the end of the closet as indicated in Figs. 2 and 3, a suitable partition 65 18 serving as the inner side wall of the closet to separate the doors from the contents of the closet.

When the doors are extended or opened out to close the front of the closet as shown in Fig. 1, they may, of course, be provided with suitable rollers, or engaging means at the top, such as 19, and similar rollers or engaging means, such as 20 may be provided at the bottom so that when the handle 9 is 75 pulled outwardly the doors will buckle out as shown in Fig. 3, the members 19—20 sliding along the groove 17, after which they may be pushed into the side chamber formed by the inner wall 18, along the guides 15—16, 80 which are engaged by the members 19—20 respectively, thus occupying the position shown at the left in Fig. 2, and of course, it will be understood that the mechanism on the other side of the closet or case is the 85 same. The rods 10—11 being slidably connected insure the vertical alignment of the doors thus preventing the wedging or kinking of the same.

Of course, it will be understood that various modifications may be made in the construction and arrangement of parts without departing from the spirit of invention as claimed.

I claim:

In combination with a chamber of the class described, a closure comprising foldable sections, a guide at the top and bottom

along the front of said chamber and guides at the side of said chamber, a rod pivotally secured to said chamber at one end and pivotally secured to said sections at the other 5 end said last mentioned pivot being adapted to slide within said guides at the side of said chamber.

In testimony whereof I hereunto affix my signature in the presence of two witnesses.

JOHN THOS. FAIRHURST.

Witnesses:

DAVID H. DOUGLASS,
THOMAS A. HILL.
